UNITED STATES PATENT OFFICE

2,435,812

AMALGAMATOR WITH PRELIMINARY
SLIME REMOVER

Claude J. Whitlock, San Bernardino, Calif.

Application February 6, 1943, Serial No. 475,016

2 Claims. (CL 209—42)

1

This invention relates to new and useful improvements in separators such as are employed for separating valuable metals from ore and more especially to amalgamators with preliminary slime removers.

The principal object of the present invention is to provide a separator of the character indicated which in use will increase the ore tonnage handled per hour over correspondingly sized machines now on the market.

Another important object of the invention is to provide a separator of the character indicated which is self-operating and requires little human attention.

Still another important object of the invention is to provide such a separator which will be capable of separating valuable metals from ore in a precision-like manner.

Other objects and advantages of the invention will become apparent to the reader of the following description.

In the drawings:

Figure 1 is a side elevational view of the machine.

Figure 2 is a top plan view.

Figure 3 is a horizontal section on line 3—3 of Figure 1.

Figure 4 is a vertical sectional view through the machine.

Figure 5 is a section on line 5—5 of Figure 4.

Figure 6 is a section on line 6—6 of Figure 4.

Figure 7 is an enlarged horizontal section on line 7—7 of Figure 4.

Figure 8 is an enlarged fragmentary detailed sectional view on line 8—8 of Figure 7.

Figure 9 is a fragmentary side elevational view, partly in section, showing the jarring means.

Figure 10 is an enlarged horizontal sectional view taken substantially on line 10—10 of Figure 4.

Figure 11 is a horizontal sectional view taken substantially on line 11—11, looking upwardly.

Figure 12 is an enlarged detailed sectional view showing one of the trip gates for release of concentrated metal.

Referring to the drawings wherein like numerals designate like parts, it can be seen that numeral 5 denotes a vertically disposed shell, having a frusto-conical-shaped bottom 6, inverted, and having at its central portion a depending well 7.

2

formed with a plurality of openings 8 in the bottom thereof.

Numerical 9 denotes a hollow shaft which extends vertically through the shell 5. The upper end of the shaft 9 has a drive pulley 10, and brace members 11 extend from the upper portion of the shell 5 to a bearing 12 for the shaft 9.

An inverted frusto-conical-shaped hopper 13 is located at the top of the shell 5 for directing crushed ore onto a conical pan 14, below which is located a converting bowl 15. The top side of the pan 14 has a plurality of concentrically disposed and spaced ribs 16, the pan 14 being formed with openings 17 arranged in rows adjacent said ribs 16. The bowl 15 is welded or otherwise secured to the shaft 9 just below openings 18 formed in the shaft 9.

Below the pan 14 is a converting cone 19, the lowermost portion of which is cut away to define a passageway 20, so that material can pass downwardly and into an amalgamating chamber 21, which chamber has a bottom 22, raised at its central portion, at which point a sleeve 23 is provided, extending upwardly around the shaft 9 and provided with a cap 24, thus providing a water seal. Arms 25 project laterally from the shaft 9 and carry a plurality of depending fingers 26, this structure defining rakes for operation in the amalgamating chamber 21.

A circumferential jacket 27 is provided on the shell 5 at the amalgamating chamber 21 and at the upper portion of the amalgamating chamber 21, the shell 5 is formed with openings 28 through which materials can be thrown by the fingers 26 from the chamber 21 into the jacket 27.

Below the amalgamating chamber bottom 22, the shell 5 is formed with a plurality of openings 29 for delivering the materials from the jacket 27 onto a converting cone 30. The lower portion of the amalgamating chamber 21 has an amalgam drain 31.

From the converting cone 30, the materials drop into a lower chamber 31 and at this point of the shaft 9, laterally disposed arms 32 are provided with a plurality of depending fingers 33, certain fingers 34 dipping into the bottom 6 and other fingers 35 dipping into the well 7, so as to barely agitate all materials contained in this lower chamber and its environs.

The lower portion of the shell 5 has a jacket 36

communicating with the lower chamber 31 through openings 37 and obviously this jacket serves to catch tailings thrown off by the rake fingers 33, 34 and 35, numeral 38 denoting a chute for the tailings.

As shown in Figures 4 and 9, the shell 5 has vertical legs 40 and horizontal members 41 connect the legs, and also serve to support a bearing 42.

Secured on the bearing 42 is a plate 43 upon which is located a cam 44. Attached to the lower portion of the shaft 9 is a collar 45 which has a cam surface cooperative with the cam 44, the object being that at every revolution of the shaft 9, the shaft 9 is raised and then suddenly dropped. This preferably occurs about 400 times a minute due to the 400 R. P. M. of the shaft.

To reach the compartments 21 and 31, the side of the shell 5 is provided with doors 46, 47 and suitable detent means 48 is provided for each of these doors.

The openings in the bottom of the well 7 through which the concentrated metals are allowed to pass are normally closed by flap valves 50 (see Fig. 10) hingedly secured, as at 51, to plates 52 which in turn are secured to the bottom of the well 7.

Each of the flap valves 50 has an angular bracket 53 secured thereto which depends a substantial distance below the well and on this is pivotally secured a short arm 54 apertured to receive one end of an elongated tension spring 55, this spring extending to an anchoring hook 56 which may be welded or otherwise secured to the plate 52 of an adjacent valve structure.

The lower portion of the shaft 9 has several fingers 57 projecting laterally therefrom and these, when the shaft 9 is rotating, strike the depending legs 54 and cause successive opening of the valve flap plates 50.

In the event it is desired to maintain the valve members 50 closed, the leg members 54 can be swung upwardly toward the left, as shown in Figure 12, and the springs 55 will serve to maintain these legs in this inoperative position.

The ore materials mixed with water are fed into the hopper 13 in any suitable manner to issue from said hopper, under the influence of gravity, into the pan 14 which, together with the converting bowl 15, functions as a centrifugal separator draining the water and slime therefrom and thereby reducing the materials to solids which are thrown out of the pan, under centrifugal force, to fall into the cone 19. The water and slime drain through the openings 17 in the pan 14 into said bowl 15 and are directed thereby through the openings 18 into the shaft 9 to discharge out of the bottom of said shaft. The cone 19 directs the solids to the opening 20 to issue from said opening and fall into the bottom of the amalgamating chamber 21. In said chamber 21, the solids are agitated by the fingers 26, the heavier solids gravitating to the bottom of said chamber, for instance, the free gold to be caught by mercury provided in the bottom of said chamber 21. The amalgamated heavier solids are drawn off through the drain 31. The lighter solids rise to the top in said chamber 21 and are forced out of the same by the fingers 26 and under the action of centrifugal force into the jacket 27, by way of the openings 28. From the jacket 27, said lighter solids pass into the cone 30 by way of the openings 29. From the cone 30, the lighter materials discharge into the lower chamber 31 in which, under the agitating action of the rake

fingers 33, and 34, the tailings rise to the top and are thrown, under the action of centrifugal force, into the jacket 36 by way of the openings 37 to discharge out of the chute 38. The heavier matter in the chamber 31 is concentrated in the bottom thereof to discharge out of the well 7 intermittently under control of the valves 50 operated in the manner already described.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

1. In a separator of the class described, an upright shell having a central transverse partition therein dividing the same into an upper and a lower compartment, respectively, for successively receiving ore material therein, an axial hollow shaft extending through said shell for rotation and endwise reciprocation and having upper side inlet apertures therein, an annular feed hopper in the top of the shell for receiving ore material and water and having a discharge aperture surrounding said shaft for discharging ore material and water into the top of the upper compartment, a downwardly tapering bowl fixed concentrically on said shaft for rotation thereby beneath said hopper with the bottom thereof communicating with said inlet apertures and for directing slime and water from the ore material to said apertures to pass into said shaft and drain out of the same, a downwardly tapering pan for receiving the ore material from said hopper fixed in the top of said bowl for rotation thereby and having agitating ribs and drain apertures therein adapting the same to function as a centrifugal and gravity separator for separating the solids in the ore material from the water and slime and discharging the solids over the edge of the pan, while the slime discharges through the drain apertures in said bowl, amalgamating means in the bottom of the upper compartment, for amalgamating the solids discharged from said pan, means in the bottom of the lower compartment for concentrating the heavier solids in said bottom and separating and discharging tailings therefrom, and means to rotate and reciprocate said shaft.

2. In a separator of the class described, an upright shell having a central transverse partition therein dividing the same into an upper and a lower compartment, respectively, for successively receiving ore material therein, said partition being of conical form, an axial hollow shaft extending through said shell and partition for rotation and endwise reciprocation and having upper side inlet apertures therein, an annular feed hopper in the top of the upper compartment for receiving ore material and water and having a discharge aperture surrounding said shaft, a downwardly tapering bowl fixed concentrically on said shaft for rotation thereby beneath said hopper with the bottom thereof communicating with said inlet apertures and for directing slime and water from the ore material to said apertures to pass into said shaft and drain out of the same, a downwardly tapering pan for receiving ore material and water from said hopper fixed in the top of said bowl for rotation thereby and having agitating ribs and drain apertures therein adapting the same to function as a centrifugal and gravity separator for separating the solids in the ore material from the slime and water and dis-

charging the solids over the edge of the pan while the slime and water discharges through the drain apertures into said bowl, and means to rotate and reciprocate said shaft.
